UNITED STATES PATENT OFFICE.

WILLIAM S. MULLER, OF CEDAR RAPIDS, IOWA.

COMBINED PIANO-SEAT AND MUSIC-CABINET.

1,219,988.

Specification of Letters Patent. Patented Mar. 20, 1917.

Application filed January 15, 1914. Serial No. 812,251.

To all whom it may concern:

Be it known that I, WILLIAM S. MULLER, a citizen of the United States, residing at Cedar Rapids, in the county of Linn and State of Iowa, have invented certain new and useful Improvements in Combined Piano-Seats and Music-Cabinets; and I do hereby declare the following to be a full, clear, and exact description of the invention, such as will enable others skilled in the art to which it appertains to make and use the same.

This invention relates to combined piano seats and music cabinets and has for its object the production of a piano seat and cabinet of economical construction and increased capacity, wherein the music is readily accessible to the performer without the necessity of leaving the seat.

20 A further object of this invention is the production of a piano seat and music cabinet provided with trays of very thin metal of peculiar construction whereby a greater number of sheets of music may be stored 25 therein.

With these objects in view, the invention consists in the construction, combination and arrangement of parts hereinafter fully described and claimed and illustrated in the 30 accompanying drawings, in which,—

Figure 1 is a perspective view of my combined piano seat and music cabinet the same being shown in closed position.

Fig. 2 is a similar view to Fig. 1 excepting the seat being raised and the doors open for exhibiting the interior thereof, one of the trays being withdrawn and resting against one of the doors.

Fig. 3 is a vertical transverse sectional view of the device showing the arrangement of the slides having one of the trays arranged thereon within the same.

Like reference characters denote similar parts throughout the several views of the drawings and reference being had to the same, 1 denotes the piano seat supported by the four posts or legs 2 and arranged at the rear thereof and supported between the rear legs 2 is the upper rail 3 and to which rail 45 the seat 1 is secured at one side edge thereof by the hinges or other connections 6 and arranged adjacent the lower end of the legs 2 is the bottom rail 4 and mounted between the rails 3 and 4 and the rear legs 2 is the 50 panel 5. Arranged at the ends of the seat 1 and at the upper portion of the legs 2 is

the top rail 7 and also adjacent the lower ends of the legs 2 is the complement rail 8 and between the rails 7 and 8 is also mounted an end panel 9. At the upper front portion of the seat 1 and extending between the front legs 2 is the upper rail 10 corresponding with the rail 3 at the rear of the seat and also arranged adjacent the bottom of the front legs 2 is the bottom front rail 11 corresponding with the rear lower rail 4. Arranged between the upper rail 10 and the lower rail 11 at the front of the seat 1 are the door frames 12 provided with the panels 13 having arranged thereon the harps 13' or any other musical design. The doors 12 are each secured to the respective contiguous legs 2 through the medium of the hinges 14, the doors 12 being also provided with the knobs or handles 15 for opening and closing the same.

Arranged within the seat 1 and in a plane with the upper edges of the bottom rails 4, 8 and 11 is the bottom 16 and above which bottom 16 adjacent the upper portion of the seat is arranged a supplemental bottom 17, the space between the bottom 16 and the supplemental bottom 17 providing a compartment 19 for the current music, the space between the supplemental bottom 17 and 85 the seat 1 providing an auxiliary compartment for the reception of the music after the playing of the same.

Arranged within the compartment 19 at the front and rear of the center portion 90 thereof are vertical strips 21. Upon the inner sides of said vertical strips and the inner sides of the ends of the seat frame, are parallel horizontal strips or slides for supporting a plurality of trays 25 adapted to 95 rest and slide thereon.

These trays are formed of sheet metal for economizing space and each tray is provided with an upwardly extending rear flange 26 to form a follower for the sheets 100 of music, an upwardly extending side flange 27 obviating the necessity for a solid vertical partition at 21, and a depending flange 28 at the front edge of the tray may be used as a handle in withdrawing the tray.

This sheet metal tray, as above stated, economizes in space so that more sheets of music may be accommodated, is light and cheap to make and easily handled and can be readily and closely nested for shipment or 110 storage.

It is to be noted that the rails, the posts

and panels forming parts of my invention are secured together by dove tailing or rabbeting or any other suitable manner for securing the parts together which joints are 5 illustrated at 29 in Fig. 2 of the drawing, and which figure also shows the music 30 arranged upon the trays 25 within the compartment 19 and also the music 31 as placed in the auxiliary compartment 20.

10 My combined piano seat and music cabinet may be constructed of any material suitable for the same and may be ornamented in any desirable manner. For practical use the performer sits upon the seat 1 while in 15 the act of playing and should it be desired to change to another sheet of music all that is required is to simply rise, open one of the doors 12 withdraw the proper tray 25 having a number of sheets of music arranged 20 thereon in either classified or alphabetical order and after withdrawing the desired sheet of music the one played may be deposited in the auxiliary receptacle 20 by the raising of the seat 1 after which operation 25 the seat may be lowered to its closed position and the playing resumed. It is, therefore, clearly obvious that by my invention the necessity for the performer leaving his seat in order to secure another sheet for 30 playing is wholly obviated, my device being also an ornament of furniture for parlor use as well as for the purpose for which the same is designed.

While I have shown the preferred form of my invention, I hereby reserve the right 35 to make such variations and alterations therein as I may deem expedient and which do not depart from the spirit of this invention or conflict with the scope of the claim.

Having thus fully described my invention, what I claim as new and desire to secure by Letters Patent is:

A combined piano seat and music cabinet comprising a main body provided with a 45 central compartment having vertical strips at the center of the front and rear thereof, parallel horizontal supports connecting the strips, similar parallel horizontal supports secured to the inner sides of the ends of 50 the compartment, and trays of thin solid material slidably supported on said horizontal strips, said trays having vertical upwardly extending flanges at their inner ends, downwardly extending flanges at their outer 55 or front ends and upwardly extending flanges on their sides which are located at the center of the compartment.

In testimony whereof I have signed my name to this specification in the presence of two subscribing witnesses.

WILLIAM S. MULLER.
